UNITED STATES PATENT OFFICE.

BRUNO GREIF, OF TACOMA, WASHINGTON.

SHIP-PROPELLER.

1,155,654.

Specification of Letters Patent.

Patented Oct. 5, 1915.

Application filed August 10, 1914. Serial No. 855,993.

To all whom it may concern:

Be it known that I, BRUNO GREIF, a citizen of the United States, and a resident of Tacoma, in the county of Pierce and State 5 of Washington, have invented a certain new and useful Improvement in Ship-Propellers, of which the following is a specification.

This invention relates to means for propelling ships and is especially an improvement 10 in that class of propellers known as stern wheels.

It has for its objects to provide an improved form of wheel which will grip the water better without the same amount of 15 slip and disturbance to the water, thus providing a greater thrust for the same amount of energy expended by the propelling prime mover; to provide a propeller which will adjust itself to the level of the ship in the 20 water and to the waves through which the ship is passing; and to provide means whereby the thrust and therefore the speed may be controlled. I attain these and other objects by the devices, mechanisms and arrangements illustrated in the accompanying 25 drawings, in which—

Figure 1 is a side elevation of the stern of a ship equipped with my improved propeller, showing however the propeller in 30 vertical longitudinal section; Fig. 2 is a rear elevation of a portion of the propeller; and Fig. 3 is a section of a portion thereof.

Similar numerals of reference refer to similar parts throughout the several views.

The ship 1 may be of any type and for any purpose, and is provided with a suitable prime mover, such as a steam or oil engine. One or more thrust arms 2 are pivotally secured to the end of the ship 1 at suitable 40 points therein, the said arms being of equal lengths and their pivots 3 having a common horizontal axis positioned transversely of the ship. The number of said arms 2 will depend on the width and weight of the ship 45 1; as many arms being used as can conveniently be placed between the various units of the propeller. These arms 2 are all secured together at their outer or free ends by means of a shaft 4 which is rigidly secured to each 50 arm. The arms and shaft are free to move vertically about the centers of the pivots 3. The shaft 4 is preferably made hollow.

The propeller is preferably divided into independent units, each separately driven, 55 and each unit is subdivided into smaller sections. All the units are similar and there-

fore the description of one unit will be understood as applying to all alike. The unit of propeller consists of a plurality of plates 5, dividing it transversely into sections, 60 which are journaled with water-tight bearings on the horizontal stationary shaft 4 and rotate thereon. The plates 5 are equal in diameter and extend beyond the extreme reach of the hereinafter described paddles. Large 65 drums 6 are formed within the unit and are rigidly connected to the plates 5 with watertight joints, the drums being coaxial with the shaft 4. The drums 6 act as buoyant floats which sustain the propeller in the 70 water. Bent plates 7 are also secured between the plates 5, outside of the drum 6, and form the paddles. The preferable arrangement of said plates 7 in a section is that they extend between two points near 75 the periphery of the plates 5 and are bent to contact with the drum 6. The wheel thus formed will have a very few paddles which are widely separated, thus giving time for the water to fill in the space between the 80 paddles and giving the paddle a grip on a greater relative quantity of comparatively still water. The plates 7 in two adjacent sections of a unit are arranged so that their apexes are not in line with each other. The 85 adjacent sections follow each other successively as shown in the drawings.

The plates 5 prevent the water in one section rushing sidewise into the adjacent section and therefore prevent loss of energy 90 since the water is all driven directly backward and reacts in a straight forward direction. Since the wheel is floating on the water its contact therewith will be uniform independent of loading conditions on the 95 ship and of wave motion of the sea. The plates 5 protect the plates 7 from damage from logs, rocks, etc.

It will be seen from Fig. 3 that it is practically impossible for any water to enter the 100 end drums 6 of a unit because it would have to pass through a bearing which is normally out of water and which is therefore practically watertight; but should a little water leak thereinto it is evident that it will lie at 105 the lowest point thereof and will never reach the bearing of the next plate 5, and therefore the interior of the next drum 6 will be uniformly dry. The leakage into either of the outer drums 6 may be removed by a pipe 110 8 leading to its lowest point and connecting to a suitable pump in the ship (not shown)

through the hollow shaft 4 and through one of the arms 2 (Fig. 3).

When the propellers are driven by electricity (generated on the ship or otherwise), 5 I mount the driving motor 9 directly on the fixed shaft 4 within one or more of these inner drums 6 (Figs. 1 and 3), connecting the rotating part of the said motor (either directly as shown, or by gear) with the rotating drums and driving the said unit 10 through the drums. The wires 10 which conduct the electric energy to the motor are conveyed thereto through the arms 2 and the hollow shaft 4. It is evident, however, 15 that each unit may be driven by cable, chains, links, or any other suitable mechanism, but I prefer to use electricity because it gives a greater control of the several units without any complicated mechanism to secure 20 the control. Thus it will be seen that the ship may be driven by all its units or any one or more may be slowed down,

stopped, or reversed, thus giving a very large degree of control of the speed and direction of motion of the ship. 25

Having therefore described my invention, what I claim is:—

In a ship propeller, the combination with a ship; thrust arms pivotally secured thereto; a nonrotating hollow shaft joining the ends of said arms; a plurality of circular disks mounted on said shaft and rotating thereon; cylindrical buoyant floats joining said disks and mounted concentric with said shaft, and being of less diameter than said disks; paddles extending outward from the floats and secured to the disks; and a suction pipe passing from the interior of said hollow shaft to the lowest point in said buoyant float to remove the water therefrom. 30 35 40

BRUNO GREIF.
